LOCOMOTIVE TENDER

Filed Dec. 27, 1932

UNITED STATES PATENT OFFICE

1,969,372

LOCOMOTIVE TENDER

Francis Hogg, Wesleyville, Pa., assignor to The Standard Stoker Company, Incorporated, a corporation of Delaware

Application December 27, 1932, Serial No. 648,836

24 Claims. (Cl. 105—234)

This invention relates to improvements in locomotive tender construction and has for its principal object the provision of efficient means for urging fuel from the rear slope sheet of the fuel bunker onto the shovelling platform.

A further object of this invention is to equip locomotive tenders with a plurality of conveyors which are mounted on the rear slope sheet of the fuel bin, the conveyors being arranged in spaced relation transversely of the rear slope sheet and each being independently operated.

A still further object of the invention is the provision of means for urging fuel from the rear slope sheet of the fuel bunker onto the shovelling platform of the tender, such means comprising a plurality of conveyor screws mounted on the rear slope sheet in spaced relation transversely thereof and being driven independently from their forward ends by mechanism which is mounted in an alcove beneath the shovelling platform of the tender.

Other objects of this invention reside in the particular arrangement of parts and in their cooperation one with another as set forth in the annexed specification accompanying the drawing, in which

Fig. 1 is a central vertical longitudinal section through the forward portion of the improved tender;

Fig. 2 is a section taken on the line 2—2 of Figure 1;

Fig. 3 is a section taken on the line 3—3 of Figure 1 with some parts in elevation, and

Fig. 4 is a section taken on the line 4—4 of Figure 2.

On the drawing, the locomotive tender is designated at A and comprises a tank 10 mounted on the base frame 11. The tank 10 consists of a water compartment or cistern 12 and a fuel bin 13 which is separated from the cistern by side slope sheets 14, 15, a rear slope sheet 16 and a floor 17, the forward portion 18 of which forms the fuel shovelling platform. The usual coal gate 19 is mounted between the bulkheads 20, 21 above the floor 17 and may be opened in any suitable degree to permit coal to fall onto the shovelling platform 18.

Usually, the fuel bin 13 is of such length, or the rear sheet 16 is inclined at such a gradual slope, that the entire coal supply is not within convenient reach of the fireman when the fuel bin is partly depleted. In order to deliver such coal onto the shovelling platform which coal does not fall by gravity thereon, I mount a plurality of screw conveyors such as 22, 23 and 24 on the

rear slope sheet 16. These screw conveyors are spaced transversely of the rear slope sheet and at their upper ends each are journalled in a bearing such as 25.

The screw conveyors 22, 23 and 24 are each driven from their forward end by suitable mechanism encased in the housing 26 which is disposed in an alcove 27 located at the forward end of the tender beneath the shovelling platform 18 and separated from the water compartment by the usual partition plates. Formed with the housing 26 are the bearings 28, 29 and 30 which form journals for the shafts 31, 32 and 33 respectively. These bearings extend through openings as at 17a in the floor 17. The screw conveyors 22, 23 and 24 are each in driving engagement with their respective shafts 31, 32 or 33, and are enlarged in diameter adjacent these bearings in order to facilitate the passage of coal thereover. From their enlarged lower ends, the conveyor screws taper upwardly, and at their lower ends the impelling faces of the screw conveyors extend across the width of the fuel bin floor whereby coal may be advanced across the entire width of the shovelling platform. The shafts 31, 32 and 33 are housed within the housing 26 and are not journalled in the wall 26a but terminate some distance short thereof. Shafts such as 31a, 32a and 33a are each journalled in the wall 26a and have their axes in alignment with the shafts 31, 32 and 33 respectively. One of these shafts, such as 32a, has connected thereto a universal joint 34 which transmits power from any suitable source through the shaft 35 for driving the screws 22, 23 and 24 in a manner which will now be described.

On each of the shafts 31a, 32a and 33a, intermeshing gears such as 36, 37 and 38 are securely mounted and each of these gears is provided with a clutch element such as 39. Rearward of these is clutch elements, a slidable clutch 40 is mounted on each shaft 31, 32 and 33 and is arranged to be slid into and out of engagement with its respective clutch element 39. Each of the slidable clutches 40 is keyed to its respective shaft, and thus when they are caused to engage their respective clutch element 39, motion will be transmitted to the screw conveyors.

Preferably, each of the screw conveyors 22, 23 and 24 is driven independently of one another and for this reason each slidable clutch 40 is shifted by yokes or shifters such as 41, 42 and 43, pivoted immediately above the shafts 31, 32 and 33 respectively. The yokes 41, 42 and 43 are each manually operated by the hand levers 44, 45 and 46.

46 respectively, at the forward end of the tender. The hand levers 44 and 45 are located adjacent the right bulkhead 20, and the lever 46 is located adjacent the left bulkhead 21. The lever 5 44 is mounted on a shaft 47 which extends transversely of the tender and is supported from the floor 17 by brackets such as 48. The shaft 47 is provided with an arm 49 which is connected to the yoke 41 by a link 50, whereby movement of 10 the lever 44 will engage or disengage the slideable clutch 40 with the clutch element 39. Similarly, the levers 45 and 46 are mounted on the hollowed shafts 51 and 52 respectively, each of which is mounted over the shaft 47, the hollowed shaft 15 51 is apertured as at 53 to allow for movement of the arm 49. Each of the shafts 51 and 52 is provided with an arm 54 and 55 for operating the shifting yokes 42 and 43 respectively, through the medium of connecting links similar to the one 20 shown at 50 in connection with the operation of the yoke 41.

Whenever the fireman has used all of the coal which is within convenient reach, he then places the hand levers 44, 45 and 46 in a position to 25 cause the slideable clutch 40 to engage the clutch element 39 of the gears 36, 37 and 38. He then applies power to the shaft 35; the screws 22, 23, and 24 will then urge the coal forwardly onto the shovelling platform 18, and when a sufficient 30 amount has been delivered, the power to the shaft 35 is stopped and the hand levers 44, 45 and 46 are moved to their normal position. Whenever it is desired to move coal from a selected portion of the fuel bin, the screw conveyor 35 in that particular portion may be operated independently of the other screw conveyors by moving the proper hand lever.

From the foregoing, it will be apparent that I have constructed a novel fuel conveyor for use 40 in connection with locomotive tenders. The use of this construction is especially adaptable in such instances where the rear slope sheet is pitched at a very moderate angle and is of such length that the use of the ordinary coal pusher of the reciprocating type would not be advantageous because of the long stroke which the reciprocating engine would have to make in order to deliver coal onto the shovelling platform.

Having described my invention, I now make 50 claim to the following as new and useful in the particular art to which this invention relates.

I claim:

1. A locomotive tender having a fuel bin provided with a floor and a slope sheet, a screw conveyor mounted on the slope sheet, and means for driving said screw conveyor from its forward end, said means being disposed beneath said fuel bin floor.

2. A locomotive tender having a fuel bin provided with a floor and a slope sheet, an alcove at the forward end of the tender beneath said floor, a screw conveyor mounted on the slope sheet, and means for driving said screw conveyor from its forward end, said means being disposed within 65 said alcove.

3. A locomotive tender having a fuel bin provided with a floor and a slope sheet, a plurality of screw conveyors on said slope sheet, and means for driving each of the screw conveyors independently from their forward ends, said means being disposed beneath said fuel bin floor.

4. A locomotive tender having a fuel bin provided with a floor and a slope sheet, an alcove at the forward end of the tender beneath said floor, 75 a plurality of screw conveyors on said slope

sheet, and means for driving each of said screw conveyors independently from their forward ends, said means being disposed within said alcove.

5. A locomotive tender having a fuel bin provided with a floor and a slope sheet, a screw conveyor mounted on the slope sheet, and means for driving said screw conveyor from its forward end, said means being disposed beneath said fuel bin floor and including a housing having a bearing formed therewith, a shaft journalled in said bearing and extending into said housing, said screw conveyor being in driving engagement with said shaft, a clutch element in said housing arranged to be in driving engagement with said shaft, and means for imparting motion to said clutch element.

6. A locomotive tender having a fuel bin provided with a floor and a slope sheet, a screw conveyor mounted on the slope sheet, and means for driving said screw conveyor from its forward end, said means being disposed beneath said fuel bin floor and including a housing having a bearing formed therewith, a shaft journalled in said bearing and extending into said housing, said screw conveyor being in driving engagement with said shaft, a second shaft in said housing in alignment with the first named shaft, a clutch element secured to said second named shaft, a slideable clutch in driving engagement with the first named shaft, a shifter for sliding said clutch in or out of engagement with said clutch element, and means for imparting motion to said second named shaft.

7. A locomotive tender having a fuel bin provided with a floor and a slope sheet, a screw conveyor mounted on the slope sheet, and means for driving said screw conveyor from its forward end, said means including a shaft in driving engagement with said screw conveyor and a bearing for said shaft extending into the fuel bin, the diameter of the conveyor screw being larger at its end adjacent said bearing than at its opposite end.

8. A locomotive tender having a fuel bin provided with a floor and a slope sheet, a plurality of screw conveyors mounted on the slope sheet, and means for driving each of said screw conveyors independently from their forward ends, said means being disposed beneath said fuel bin floor and including a housing having gears formed therewith, a shaft for each of said screw conveyors, said shafts journalled in their respective bearings and being in driving engagement with their respective screw conveyors, a clutch element in said housing for each of said shafts, a clutch member slidably mounted on each of said shafts and in driving engagement therewith, a shifter for each of said clutch members, said shifters arranged to move said clutch members along said shafts for selectively engaging their respective clutch elements, and means for imparting motion to said clutch elements.

9. A locomotive tender having a fuel bin provided with a floor and a slope sheet, a plurality of screw conveyors mounted on the slope sheet, and means for driving each of said screw conveyors independently from their forward ends, said means being disposed beneath said fuel bin floor and including a housing, a plurality of shafts journalled in said housing, each of said screw conveyors being in driving engagement with its respective shaft, a plurality of meshing gears in said housing, a clutch element associated with each of said gears, a slideable clutch member in driving engagement with each of said shafts,

- means for imparting motion to said gears, and a shifter for sliding each of said clutch members independently along its respective shaft for engaging or disengaging said clutch member with its respective clutch element. 80
10. A locomotive tender having a fuel bin provided with a floor and a slope sheet, a plurality of screw conveyors mounted on the slope sheet, and means for driving each of said screw conveyors independently from their forward ends, said means being disposed beneath said fuel bin floor and including a housing, a plurality of shafts journaled in said housing, each of said screw conveyors being in driving engagement with its respective shaft, a plurality of meshing gears in said housing, a clutch element associated with each of said gears, a slideable clutch member in driving engagement with each of said shafts, means for imparting motion to said gears, a shifter for sliding each of said clutch members independently along its respective shaft for engaging or disengaging said clutch member with its respective clutch element, and a plurality of hand levers at the forward end of the tender for operating said shifters. 85
11. A locomotive having a fuel bin provided with a floor and a slope sheet, a water compartment, an alcove at the forward end of the tender beneath said fuel bin floor, partition plates separating said water compartment from said fuel bin and said alcove, a screw conveyor mounted on said slope sheet, and means for driving said screw conveyor from its forward end, said means being disposed in said alcove and including a housing having a bearing formed therewith, a shaft journaled in said bearing and extending into said housing, said screw being in driving engagement with said shaft, a clutch element in said housing arranged to be in driving engagement with said shaft, and means for imparting motion to said clutch element. 90
12. A locomotive having a fuel bin provided with a floor and a slope sheet, a water compartment, an alcove at the forward end of the tender beneath said fuel bin floor, partition plates separating said water compartment from said fuel bin and said alcove, a screw conveyor mounted on said slope sheet, and means for driving said screw conveyor from its forward end, said means being disposed in said alcove and including a housing having a bearing formed therewith, a shaft journaled in said bearing and extending into said housing, said screw being in driving engagement with said shaft, a second shaft in said housing in alignment with the first named shaft, a clutch element secured to said second named shaft, a slideable clutch in driving engagement with the first named shaft, a shifter for sliding said clutch in or out of engagement with said clutch element, and means for imparting motion to said second named shaft. 95
13. A locomotive having a fuel bin provided with a floor and a slope sheet, a water compartment, an alcove at the forward end of the tender beneath said fuel bin floor, partition plates separating said water compartment from said fuel bin and said alcove, a screw conveyor mounted on said slope sheet, and means for driving said screw conveyor from its forward end, said means being disposed in said alcove and including a housing having a bearing formed therewith, a shaft journaled in said bearing and extending into said housing, said screw being in driving engagement with said shaft, a second shaft in said housing in alignment with the first named shaft, a clutch element in driving engagement with said second named shaft, a shifter for sliding one of said clutches into or out of engagement with the other, and means for imparting motion to said second named shaft. 100
14. A locomotive tender having a fuel bin provided with a floor and a slope sheet, a screw conveyor mounted on the slope sheet, and means for driving said screw conveyor from its forward end, said means being disposed beneath said fuel bin floor and including a housing having a bearing formed therewith, a shaft journaled in said bearing and extending into the housing, said screw conveyor being in driving engagement with said shaft, a second shaft in said housing in alignment with the first named shaft, a clutch element in driving engagement with said second named shaft, a clutch member in driving engagement with the first named shaft, a shifter for sliding one of said clutches into or out of engagement with the other, and means for imparting motion to said second named shaft. 105
15. A locomotive tender having a fuel bin provided with a slope sheet and a shovelling platform at the forward end of the tender, and a plurality of screw conveyors mounted on said slope sheet for advancing fuel from said fuel bin onto said shovelling platform, the fuel impelling surfaces of the several screw conveyors at their lower ends extending substantially the full width of said shovelling platform and the diameters thereof tapering upwardly toward their upper ends, said conveyors being disposed angularly with respect one to the other. 110
16. A locomotive tender having a fuel bin provided with a slope sheet and a shovelling platform at the forward end of the tender, a plurality of screw conveyors mounted on said slope sheet for advancing fuel from said fuel bin onto said shovelling platform, said screw conveyors being driven from their forward ends, and a bearing for the lower end of each screw, the diameters of said screw conveyors tapering upwardly and at their lower ends the fuel impelling surfaces of the several screw conveyors extending substantially the full width of said shovelling platform. 115
17. A locomotive tender having a fuel bin provided with a floor and a slope sheet, an alcove beneath said floor forward of the slope sheet, a screw conveyor mounted on the slope sheet, means for driving said conveyor, said means being disposed within said alcove and penetrating said floor. 120
18. A locomotive tender having a fuel bin provided with a floor and a slope sheet, a screw conveyor mounted on the slope sheet, and means for driving said screw conveyor, said means including a shaft operatively associated with said screw conveyor and extending through said floor. 125
19. A locomotive tender having a fuel bin provided with a floor and a slope sheet, a screw conveyor mounted on the slope sheet, means for driving said screw conveyor, said means including a shaft operatively associated with said screw conveyor and extending through said floor, and a bearing for said shaft mounted to the fuel bin. 130
20. A locomotive tender having a fuel bin provided with a floor and a slope sheet, screw conveyors mounted on the slope sheet, and means extending upward through the floor of the tender for driving said screw conveyors, said means mounted on the underside of said fuel bin floor and including a bearing, a screw shaft journaled 135
21. A locomotive tender having a fuel bin provided with a floor and a slope sheet, a screw conveyor mounted on the slope sheet, and means for driving said screw conveyor, said means including a shaft operatively associated with said screw conveyor and extending through said floor, and a bearing for said shaft mounted to the fuel bin. 140
22. A locomotive tender having a fuel bin provided with a floor and a slope sheet, screw conveyors mounted on the slope sheet, and means extending upward through the floor of the tender for driving said screw conveyors, said means mounted on the underside of said fuel bin floor and including a bearing, a screw shaft journaled 145
23. A locomotive tender having a fuel bin provided with a floor and a slope sheet, screw conveyors mounted on the slope sheet, and means for driving said screw conveyor, said means including a shaft operatively associated with said screw conveyor and extending through said floor, and a bearing for said shaft mounted to the fuel bin. 150

- in said bearing, a power shaft, means for supporting a power shaft, and means for engaging and disengaging said screw shaft with the power shaft.
5. 21. A locomotive tender having a fuel bin provided with a floor and a slope sheet, a water compartment, an alcove at the forward end of the slope sheet beneath said fuel bin floor, partition plates separating said water compartment from said fuel bin and said alcove, a screw conveyor mounted on said slope sheet, and means for driving said conveyor, said means being disposed in said alcove and comprising a support including a bearing attached to the fuel bin floor, a shaft journalled in said bearing and having a driving extension below said bearing, said screw being in driving engagement with said shaft, said extension being provided with a clutch element arranged to be in driving engagement with said extension, and means for imparting motion to said clutch element.
10. 22. A locomotive tender having a fuel bin provided with a slope sheet and a floor having an opening therein, a screw conveyor mounted on the slope sheet, and means for driving said screw conveyor including a support, a shaft in driving engagement with said screw journalled in said support and extending through said opening, and means for imparting motion to said shaft beneath the fuel bin floor.
15. 23. A locomotive tender having a fuel bin provided with a slope sheet and a floor having openings therein, fuel advancing screws on said slope sheet, means for driving said screws disposed beneath the fuel bin floor including a support, said screws having shaft extensions passing through said openings and being journalled in said support, and means for imparting motion to said shafts.
20. 24. A locomotive tender having a fuel bin provided with a floor and a slope sheet, fuel advancing screws mounted on the slope sheet, and means for driving said fuel advancing screws from their forward ends, said means being disposed beneath said fuel bin floor.

CERTIFICATE OF CORRECTION.

Patent No. 1,969,372.

August 7, 1934.

FRANCIS HOGG.

It is hereby certified that error appears in the printed specification of the above numbered patent requiring correction as follows: Page 2, line 125, claim 8, for "gearings" read bearings; and that the said Letters Patent should be read with this correction therein that the same may conform to the record of the case in the Patent Office.

Signed and sealed this 18th day of September, A. D. 1934.

Leslie Frazer
